UNITED STATES PATENT OFFICE.

HENRY JAMES HERINK, OF LONDON, ENGLAND, ASSIGNOR TO THE RELAY AUTOMATIC TELEPHONE COMPANY, LIMITED, OF LONDON, ENGLAND.

TELEPHONE SYSTEM.

1,288,411.

Specification of Letters Patent. Patented Dec. 17, 1918.

Application filed June 2, 1917. Serial No. 172,469.

To all whom it may concern:

Be it known that I, HENRY JAMES HERINK, a subject of the King of Great Britain, and resident of Marconi House, Strand, London, 5 England, have invented a new and useful Improvement in Telephone Systems, of which the following is a specification.

This invention relates to telephone systems and particularly to means for preventing the registering of calls against a caller in certain conditions, as for example:—

(a) When a connection has been broken down owing to a circuit being or becoming 15 defective.

(b) When on one of the parties being offered and accepting a trunk or other favored call, the operator severs the local connection before the termination of the conversation.

20 (c) When the called subscriber is busy.

My invention consists essentially in the provision of current varying means which in normal operating allow of the registration of a call against the party responsible 25 for the connection and the breaking down of the connection partially or wholly, but in other conditions prevent the registration of a call against the party who originated the call and break down the connection partially or wholly.

The current varying means may consist of a polarized relay at one point operated by reversal of current at a control point, or a marginal relay inoperative to one strength 35 of current and operative to another strength of current or any similar means.

It is now usual to register calls at the conclusion of the conversation by the circuit changes brought about when the receivers 40 are replaced, and my invention allows the connection to be broken down in certain conditions without the register operating.

In manual systems or in semi-automatic systems in which the connecting and metering are controlled manually, I provide current varying means which cause signals and tones to advise the operator that the connection has been interrupted. The circuits are so arranged that the depression of a 45 meter key is rendered ineffective to meter a call which has thus been interrupted, and the operator then removes the plugs, or otherwise restores the apparatus to normal. In one system described, when the signals 50 are received, the junction is also automati-

cally released and tests idle, although the plug may not have been removed from the jack.

In automatic systems the invention consists mainly in the provision of a polarized 60 or marginal relay so placed that when energized it opens directly or indirectly the calling subscriber's meter circuit, so that the meter does not register when a connection is broken down for the reasons specified before. This special relay is operated by a relay at a control point in a manner afterward to be described.

In the case of a connection on an automatic system, the guarding or release circuit is opened at the junction or trunk, or toward the subscriber's line and cut-off relays, or at both points, by a polarized or marginal relay operated from the control point, so that the connection is broken down 75 in such a way that the caller receives a tone signal, and when he replaces his receiver his meter does not register.

In an automatic system, which may be of the electro-mechanical stepping type, or entirely of relays, manual equipment is usually provided for long distance or trunk calls, and as on manual systems such calls are privileged. An operator therefore offers the privileged call and if the party 80 wanted for such call is engaged locally, but nevertheless accepts the privileged call, the local connection is broken down, but as the local conversation has not been completed 85 no charge is to be made.

Generally speaking the invention consists in the use of a relay responsive to a particular kind or strength of current and arranged to be operated from a distant point over the talking circuit to prevent metering 90 with or without releasing the talking circuit or part of it. It may be used in any of the cases above stated and in connection with any talking circuit, but it is particularly suitable for multi-office systems in 100 which the exchanges are connected by two-wire junctions. For instance, in a talking connection extending over two or more manual or automatic or manual and automatic exchanges, relays of the kind mentioned may be connected to the line at several exchanges to transmit an impulse from the distant exchange to a similar relay at the originating exchange, said relays operating 105 to release the junctions between the ex- 110

changes and to prevent metering in the manner above described.

My invention is illustrated by the accompanying drawings in which—

5 Figures 1, 1^a and 2 show the necessary apparatus and circuits for manually connecting two subscribers' stations.

Figs. 1^b and 1^c show modifications.

10 Figs. 3, 4 and 5 show the necessary apparatus and circuits for automatically connecting two subscribers' stations.

Fig. 6 shows the circuits of an additional stage, and may be inserted between Figs. 3 and 4.

15 A connection between two subscribers each connected to different manual exchanges will now be described.

In Fig. 1, S represents the calling subscriber of the first exchange A, L the line connecting S to A; T is the operator's cord circuit, and T¹ the outgoing trunk to the second exchange B.

20 Fig. 2 represents the incoming end of T¹ and B, and L² the line connecting the required subscriber S¹ to B.

25 A calling subscriber lifting his receiver completes circuit 1, energizing line relay LR which completes circuit 2, causing the calling lamp CL to glow in known manner.

30 An operator, observing the call, inserts the answering plug AP into the calling subscriber's jack AJ, thereby completing circuit 3 and energizing the subscriber's cut-off relay COR, but not subscriber's meter SM; 25 LR is thus cut out of circuit, causing CL to be extinguished.

35 Circuit 4 is also completed over the calling subscriber's telephone and relay ASR is thereby energized, shunting lamp ASL by 40 resistance R² in circuit 3^a, ASL being thus dimmed. The operator throws the key K in the direction C connecting her telephone circuit to the calling line in known manner.

The subscriber gives in the number of the 45 required exchange line, and the operator may ask for the connection over an order wire to the second exchange, or may place calling plug CP into the outgoing trunk jack CJ, thereby completing circuit 5 over the trunk

50 T¹, thus energizing relay CR in Fig. 2. Relays MCR and CSR are not energized owing to high resistance of CR. Relay CO1R is also energized over circuit 6, calling supervisory lamp CSL glowing. Relay CO1R completes circuit 7, causing the engaging lamps EL¹, EL² and the like to glow, thus denoting engagement of the trunk. CR completes circuit 8, glowing supervisory lamp S2L, thus indicating a call to the operator at the second exchange.

55 LSR energizes and partly connects up the circuit to the calling plug C1P. The second operator moves switch LK to connect up her telephone set at D to the trunk in known manner, and obtains from the operator at the

first exchange the number required. She now inserts C1P into the required number C1J, thus completing circuit 9, energizing S3R and CO2R, but not S1M. It will now be seen that circuit 8 is shunting circuit 9, 70 the resistance of LSR being low and causing S2L to be dimmed.

Ringing is now applied over C1P to the required subscriber's line in known manner, and the subscriber answering causes said 75 ringing to be disconnected, and at the same time completes circuit 10, energizing supervisory relay S1R which in turn completes circuit 11, energizing relay MHR which, switching in circuit 11^a, is rendered independent of circuit 11. S1R also switches in 80 5^a, shunting the high resistance winding of CR with its low resistance winding. Consequently CSR is energized, but not MCR (Fig. 1), which is biased against the normal 85 working current, and lamp CSL is dimmed by being shunted by R in circuit 6^a. I is an impedance to balance CSR and MCR. The calling subscriber is now able to talk to the called subscriber, the successful establishment of the connection being indicated to the A exchange operator by the dimming of lamp CSL, and to the B operator by the continued dimming of S2L. If S replaces his receiver, circuit 4 opening deenergizes 90 ASR and lamp ASL then glows fully. When S¹ replaces his receiver, circuit 10 opening causes S1R to deenergize, and opening circuit 5^a cuts out low resistance winding of CR which causes CSR to release its 95 armature. CSR opening circuit 6^a causes CSL to glow fully. The A operator, noting the glowing of ASL and CSL, depresses metering key MK, thereby switching in circuit 105 3^b, in which is connected the operator's position meter OSM which has an increased voltage connected to it. This increased voltage causes SM to operate, thus metering the call against the calling subscriber. The A operator now withdraws AP and CP from 110 jacks AJ and CJ, restoring all apparatus at exchange A to normal and causing circuit 5 to be opened. CR deenergizes, thus removing the shunt from circuit 9 and deenergizing MHR. S2L now glows fully, 115 and the B operator therefore withdraws C1P from C1J, thus restoring all apparatus at the B exchange to normal condition.

Should the connection, when S is speaking to S¹, be interrupted at the originating end 120 and plug AP be withdrawn from jack AJ, it is obvious that meter SM will not be operated. If, however, the interruption occurs at the second exchange by the withdrawal of C1P, relays S1R and S3R deenergize, and S2L will now glow over circuit 8. MMR now energizes over circuit 12, and S2L will continue to glow over circuit 8^b until this relay deenergizes. MMR switches in circuits 5^b and 5^c, the latter continuing to ener- 130

gize relay CSR, and the former imposing an increased voltage, that is, varying the current, over one line of the trunk T^1 , energizing meter control relay MCR which switches 5 in circuit 13 and energizes meter-preventing relay MPR. This causes an interrupted tone to be given from TTT over interrupter INT, by circuit 14 to S. Lamp CSL now glows fully over circuit 6 owing to circuit 10 6^a being broken by MPR. S replacing his receiver opens circuit 4 causing ASR to de-energize, thus opening 3^a and causing ASL to glow fully. The A exchange operator may depress MK, but circuit 3^b will not be 15 established owing to MPR. Neither OSM nor SM will therefore operate. She will now withdraw the plug AP, opening circuit 3, thereby releasing COR and permitting S to re-call if he so desire. Plug CP being 20 withdrawn opens circuits 5^b and 5^c to de-energize MCR, CSR and CR. Circuit 6 is also opened and CO1R de-energizes, opening circuit 7; lamps EL¹, EL², and so on, cease to glow, indicating the release of T^1 . MPR 25 also de-energizes, therefore all apparatus at the A exchange is restored to normal.

CR (Fig. 2) de-energizing opens circuit 11^a. MHR de-energizes, thus opening circuit 12. MMR is now de-energized, causing 30 S2L to be extinguished, thus returning all apparatus at B to the normal condition.

It is obvious that a modification may be made by so arranging the contacts on MPR that the depression of MK will allow OSM 35 but not SM, to operate, so that the call may actually be recorded on the operator's position meter, as shown in Fig. 1^b.

Fig. 2^a illustrates means for preventing, in a manual exchange, the registering of a 40 call against a caller if the wanted line is busy. If the wanted subscriber S¹ be busy, the operator at exchange B will insert plug C1P into jack BJ, thereby completing circuit 13 through resistance R¹³. This results 45 in the operation of S1R and consequent operation of MHR. As there is no sleeve connection on jack BJ, S3R will not have become energized, so that MMR can operate as soon as MHR has become operated, and as 50 stated above, can complete circuits 5^b and 5^c with the results already described.

Another modification which may be made 55 is to arrange that the operation of MPR shall connect an interrupter similar to INT in circuit 6^a, so that lamp CSL will flash, indicating to the A operator the breakdown of the connection. The operator, on throwing K, will receive tone from TTT. This is illustrated in Fig. 1^c. Normally CSL glows 60 over circuit 60 and is shunted by 60^a when CSR operates to dim it. If MPR is operated, CSL will be flashed by the interrupter in circuit 70, 60^a being open at MPR and the sleeve circuit maintained over circuit 80. 65 Fig. 1^a is a modification of Fig. 1. Its

operation is similar to Fig. 1, except that after MCR operates over circuit 5^b, MPR energizes over 13, opening circuit 6^a, but closing 6^b, so that CSL now glows fully. MPR disconnects circuits 5^b and 5^c, therefore 70 MCR and CSR de-energize, but MPR maintains itself over 13^a. Busy tone is given to S over circuit 14, the connection E being attached to a coil TTT and an interrupter INT similar to Fig. 1. 75

MPR is of high resistance, so that although it remains energized over 13^a, CO1R (Fig. 1) de-energizes, thereby opening circuit 7 and extinguishing engaging lamps EL. T^1 is therefore free to be engaged by 80 any other operator, the resistance of MPR preventing a busy test from being taken on the bush of jack CJ. On receiving the clearing signal from S, the operator at A will clear down the circuit in the manner described for Fig. 1. 85

A connection made between two subscribers stations in an automatic system, each directly associated with different exchanges, 90 will now be described.

In Figs. 3, 4 and 5, S² is the calling subscriber's station, L the line connecting the station to the first exchange A, T^3 a trunk between A and the second exchange B, and L² the line between the latter exchange and the called subscriber's station S³. 95

S² calls by lifting the receiver. Circuit 1 energizes line relay L2R and line L becomes connected over a pre-selector switch or relays to a junction T^2 , which has access to a first group switching stage. This is accomplished preferably by means of relays CR¹ and CR² in the manner described in application Serial No. 832,471, filed 17th April, 1914. Circuit 2 is now completed and current feeding relay IR energizes. Circuit 3 energizes relay BSR over selector connecting relay SCR, and T^2 becomes connected to an impulse responder or selector over the circuit marked AA. GR now energizes over 100 circuit 4 and renders itself independent of BSR by switching in circuit 6. The latter relay is now maintained over circuit 5. 105

CO3R and AMR, but not subscriber's meter S2M, energize over circuit 7, and FR 115 energizing over circuit 7^a. L2R is de-energized. S² now sends in impulses in known manner and causes IR to de-energize and re-energize successively. On the first impulse, IR de-energizing, ICR energizes over circuit 8 and being slow to release remains energized during a complete train of impulses, which are transmitted to the selecting device over circuit 9. 120

For the sake of clearness I will assume 125 that the first train of impulses determines the selection of the second exchange B. At the completion of the train, ICR de-energizes, SCR energizes over circuit 10 completed by the selector in any suitable manner 130

(which is not here described as it forms no part of this invention), and T^2 is connected over $C3R$ and $C4R$ to T^3 as described in Patent No. 1,195,771. The selecting device 5 is then released, circuits 5 and 9 are opened and relays $BS1R$ and SCR with $C3R$ and $C4R$ are maintained over circuit 11. During the sending of impulses GR does not de-energizes as it is slow to release, owing to 10 one of its windings being short-circuited over circuit 4^a . T^2 being connected to T^3 establishes circuit 12. $I2R$ energizes, but not $S4R$ nor polarized or marginal relay PR . $BS1R$ energizes from the selecting device 15 over circuit 13 and $G1R$, a slow release relay, energizes over 14 and, switching in 15, renders itself independent of $BS1R$, which is maintained over circuit 16. $G1R$ opens circuit 12, but the loop circuit of T^3 through 20 $I2R$ is maintained by circuit 12^a completed owing to the operation of $BS1R$ and $G1R$.

The second train of impulses is now sent in by S^2 . ICR reenergizes and the impulses are therefore repeated over T^3 , thus causing 25 $I8R$ to deenergize and reenergize successively. On the first deenergization of $I2R$, $IC1R$ energizes over circuit 17, and being slow to release does not deenergize until the train of impulses is complete. The impulses 30 are consequently repeated to a selector in the second exchange over circuit 18. When the second train of impulses is complete, ICR and $IC1R$ deenergize, and $SC1R$ energized from the selecting device is with 35 $BS1R$ maintained over circuit 19 in series with $C5R$ and $C6R$. T^3 is extended to T^4 by another selecting device (over whose contacts 19 is completed) to which subsequent impulses are sent in the manner described. 40 Eventually, when all the selecting is complete, relay FTR becomes energized over 18^a formed by the final selecting device in any suitable manner, not being part of this invention but substantially similar to the 45 manner of operating the connecting relays described in Patent No. 1,195,771 and application Serial No. 832,471, and circuit 19 is extended to this relay over contacts of RR which is operated by T^4 becoming connected, in a manner substantially similar to that described in application Serial No. 50 832,471, to L^2 by relays $C7R$ and $C8R$ and with $CO4R$ energized over circuit 20. The called subscriber's meter $S3M$ does not energize. $F1R$ has also energized over circuit 55 20^a . The selector releasing itself, relays $BS1R$, $SC1R$, $C5R$, $C6R$ and FTR are maintained in series over circuit 19.

Ringing current is now applied to S^3 over 60 circuit 21, but RGR does not energize until S^3 removes his receiver, when its second winding is switched in in place of RR . The latter relay deenergizes, cutting out the first winding of RGR which continues to be energized with $C7R$, $C8R$ and $CO4R$ over 65 22.

Ringing current is also removed from L^2 and relay $S5R$ therefore energizes over circuit 23. CLR now energizes over 24 and RCR energizes over 25, cutting out relay $I2R$. $G1R$ does not deenergize, being maintained over circuit 26. The lowest contact 70 is the last to open on relay RCR , so that relay CLR does not deenergize, but is maintained over circuit 27. The resistance of the winding of CLR is such as to energize $S4R$, 75 but not PR (Fig. 3) which is biased against the normal working current. MR now energizes over 28, and will maintain itself over circuit 29 even if $S4R$ be deenergized. Relay GR is now no longer slow, its second 80 winding being no longer short-circuited owing to circuit 4^a being opened. S^2 is now free to speak to S^3 over circuits 30 and 23 and repeating coil R . If S^3 replaces his receiver, $S5R$ deenergizes, but does not release the circuit. S^2 controls the release, and on replacing his receiver opens circuit 2 and causes IR to deenergize. This closes circuit 4^b and switches in the second winding 85 of GR as a shunt to circuit 7, AMR continuing to remain energized. The first winding of GR is now receiving current over circuit 31, and though the windings are differentially wound GR does not yet fall off, there being a balance in favor of circuit 31. 90

The increased current in circuit 7 due to the shunt causes $S2M$ to energize, and metering the call, short-circuits $CO3R$ over 7^c . The current in the second winding of GR is now increased, and is sufficient to cause it to 100 deenergize, thus releasing all the relays (shown in Fig. 3) hitherto remaining energized, and disconnecting L from T^2 and T^2 and T^3 . CLR consequently deenergizes, thereby releasing all relays shown in Figs. 105 4 and 5, also releasing T^3 from T^4 and T^4 from L^2 .

Suppose that when S^2 called S^3 , the latter subscriber was engaged on another call, the final selecting device would be unable to 110 complete the operating circuit of $C8R$, as the circuit would be broken owing to S^2 being engaged. The method of breaking this circuit forms no part of this invention, but it may be stated generally that the circuit 115 is taken through normally resting contacts of relay $CO4R$ which, as stated, becomes operated if S^3 be engaged. As $C8R$ cannot operate, RR and RCR are disabled so that circuit 19 would not be completed, resulting 120 in the release of $BS1R$, $SC1R$, $C5R$, $C6R$ and FTR . Circuit 32 is completed by the deenergization of $BS1R$ operating PR , which will cause the release of all trunks and apparatus pertaining thereto in the manner 125 explained, without causing $S2M$ to operate. Tone will be given to S^2 over circuit 7^d , until he clears by replacing the receiver on the hook switch.

I will now assume that S^2 has been con- 130

nected to S^2 in the manner described and that the former is required for a special call. A line manually or automatically operated obtains access to line L by known means and 5 S^2 is requested to take the call. If he accedes to the request, a potential is applied to the maintaining wire of the connection in known manner, as, for instance, by temporarily depressing key RRK, thus short-circuiting CR¹ and CR², also AMR by circuit 7^a, causing them to deenergize and disconnect circuit 2. IR and then GR deenergize, releasing all apparatus beyond the subscriber's line L and rendering the trunks accessible to other calls. The calling subscriber's meter being disconnected from T^2 does not receive the current necessary to operate it, and consequently no metering takes place. The special call would take place 15 over 30^a, CO3R remaining energized over 20^a and LR being cut out.

The deenergization of G1R in Fig. 4 opens circuit 19, and FTR deenergizing opens circuit 22. C7R and C8R deenergize, releasing T⁴ from L². CO4R deenergizes but 25 F1R maintains itself over circuit 23^a. S³ receives a tone from tone coil T2T denoting that the line to which he was connected is now occupied with another call. S³ on re- 30 placing his receiver opens circuit 23^a and F1R deenergizes, thus all apparatus is now normal. S² is now busy, and CO3R being energized, a false call cannot be made. The opening of circuit 7^a releasing CO3R causes 35 FR to remain energized over 7^a, unless S² has already replaced his receiver, when FR also deenergizes. When S² re-calls by re-lifting his receiver, a fresh call is initiated in the manner already described.

40 Let us now suppose that while S² and S³ were talking, S³ was required for a special call. Connection would be made to his line in known manner from jack CR1J (Fig. 5), and on S³ accepting such call, an increased 45 voltage is applied by any known method, for instance, the temporary depression of R1RK. This causes C7R, C8R and RGR to deenergize over 20^a, but CO4R continues to be maintained over 20^a, a voltage being 50 applied by the means at CR1J. The special call may now talk to S³ over 23^b, L² being disconnected from T⁴. L3R is not at any time switched in circuit. RGR opens circuit 19; consequently C5R, C6R, SC1R and 55 BS1R all deenergize, freeing T³ from T⁴. BS1R causes S5R to deenergize, but RCR maintains itself over circuit 25^a. BS1R also opens circuit 30 and varies the current, that is, applies a high voltage to one line 60 branch of T³ over circuit 32 through resistance R². PR (Fig. 3) immediately energizes, opening circuit 7. CLR deenergizes and opens circuit 26, causing G1R to deenergize, which in turn opens circuit 25^a and 65 causes RCR to deenergize. These two re-

lays are slow to release, so that I2R on this connection cannot reenergize owing to BSR releasing C3R and C4R, and disconnecting T² from T³, the latter trunk now being available for a fresh call. 70

At the first exchange (Fig. 3) PR opens circuit 7; CR¹, CR² and AMR deenergize. S² receives tone over circuit 7^a in the manner described, indicating the occupation of S³. GR deenergizes (due to the breaking of 75 circuit 4 by IR and circuit 31 by AMR) causing the break of circuit 11 and consequent release of BSR. Trunk T² is thus rendered available for a fresh call.

S² on replacing his telephone opens circuit 7^a and FR deenergizes, so that S² may make a new call if he so desires. 80

A connection set up by a calling subscriber S² connected to the first exchange A, to S³ a subscriber connected to a third exchange B, said connection to be established through an intermediate exchange D, will now be described. In this connection it will be necessary to examine further Figs. 3, 4, 5 and 6. 85 90

Fig. 3 represents the first exchange with outgoing trunk T³ leading to the second exchange D shown in Fig. 6 with trunk TT leading to the third exchange shown in Fig. 4, which connects to S³ in Fig. 5 as before 95 described.

The setting up of the connection between the two exchanges is made in a manner obviously similar to that already described. For example, the first digit impulses may 100 choose T³, the second set TT (Fig. 6) and the third and fourth sets may choose called subscriber S³ as before described.

In the operations, when T³ is connected to exchange D (Fig. 6), I3R operates, operating BS2R over circuit 34. G2R now operates over 34^a, closing 34^b, while BS2R is now maintained over 35. S² sends in the second train of impulses. IR responds as before, repeating said impulses over T³ (Fig. 3) and T³' (Fig. 6) to I3R, which also responding repeats them to a selecting device in D. At the cessation of this train of impulses, T³ is connected at TT, BS2R being now maintained over circuit 36. The third and fourth trains of impulses are now sent in, IR repeating to I3R which repeats over TT to I2R which repeats into a selecting device. Eventually said selecting device is released, and S² becomes connected to S³ in 115 the manner previously described. 120

During the repeating of impulses, IC2R (Fig. 6) operates over circuit 37 in a manner similar to ICR, thus removing condensers K and K¹, and relays P1R and S6R from the trunk. S² is now free to converse with S³, S6R but not P1R becoming operated over TT by relay CLR (Fig. 4) circuit 38, which operates CL1R over 39; RC1R operates over circuit 40, maintaining over 40^a, while 125 130

6 G2R maintains over 41. S4R operates over 42, thus operating MR as before described.

It is obvious that if S² replaces his receiver, IR deenergizing causes metering to take place on SM, and deenergizing GR releases the circuit owing to all CR relays deenergizing. Consequently CL1R (Fig. 6) deenergizes, causing G2R to deenergize. Thus this portion of the circuit is released. 10 C9R and C1OR deenergizing release the circuit shown in Figs. 4 and 5 in a manner similar to that already described.

If S³ had been engaged on another call, the release of the final selecting device releases BS1R, SC1R, C5R, C6R and FTR, thereby causing P1R and in turn PR to energize. This releases the trunks without causing metering, in the manner explained, tone being given to S over circuit 7^a until he 20 replaces his receiver.

It is also obvious that if the connection had been interrupted at the originating end, all circuits and trunks would have been released without causing metering.

25 If the interruption had taken place at the called end causing C7R and C8R to deenergize, BS1R deenergizing sends a reversed current over circuit 43, thus energizing P1R. This opening circuit 36 deenergizes BS2R, SC2R, C9R, C1OR, and thereby releases all apparatus and trunks leading to exchange B. BS2R completes circuit 44 and energizes PR (Fig. 3), thus causing the 30 release of all apparatus and trunks without causing metering, in the manner already described.

40 It may also be seen that even if a connection be interrupted at any stage, it will cause instantaneous release without metering against the calling party.

What I claim is:

1. In a telephone system, the combination of a calling subscriber's line, a meter connected therewith, a called subscriber's line 45 and means associated with a circuit connecting these lines for producing, on disconnection of that circuit, a variation in current strength to prevent the meter being operated.

50 2. In a telephone system, the combination of a calling subscriber's line, a meter connected therewith, a called subscriber's line and means associated with a circuit connecting these lines for producing, on disconnection 55 of that circuit, a reversal of current to prevent the meter being operated.

3. In a telephone system, the combination of a calling subscriber's line, a meter connected therewith, a called subscriber's line 60 and current varying means associated with a circuit connecting these lines and adapted, on disconnection of that circuit, to prevent the meter being operated and to release the connection.

65 4. In a telephone system, the combination

of a calling subscriber's line, a meter connected therewith, a called subscriber's line and means associated with a circuit connecting these lines for producing, on disconnection of that circuit, a variation in current 70 strength to prevent the meter being operated and to release the connection.

5. In a telephone system, the combination of a calling subscriber's line, a meter connected therewith, a called subscriber's line 75 and means associated with a circuit connecting these lines for producing, on disconnection of that circuit, a reversal of current to prevent the meter being operated and to release the connection.

6. In a telephone system, the combination of a calling subscriber's line, a meter connected therewith, a trunk line, a called subscriber's line, current varying means associated with the circuit comprising the two 80 subscribers' lines and the trunk line and adapted, on disconnection of the circuit, to prevent the meter operating and to release the connection and means for giving tone signals to the calling subscriber and to the 85 trunk line.

7. In a telephone system, the combination of a calling subscriber's line, a meter connected therewith, a trunk, a called subscriber's line, devices for feeding current to the 95 trunk and a relay associated with such devices biased against the normal working current and adapted to respond to a current change to prevent the meter being operated.

8. In a telephone system, the combination 100 of a calling subscriber's line, a meter connected therewith, a trunk, a called subscriber's line, devices for feeding current to the trunk, a relay associated with such devices biased against the normal working current 105 and adapted to respond to a current change to prevent the meter being operated and means for giving tone signals to the calling subscriber's line.

9. In a telephone system, the combination 110 of a calling subscriber's line, a meter connected therewith, a trunk, a called subscriber's line, devices for feeding current to the trunk and a relay associated with such devices biased against the normal working 115 current and adapted to respond to a current change to prevent the meter being operated and simultaneously to disconnect the calling subscriber's line from the trunk.

10. In a telephone system, the combination 120 of a calling subscriber's line, a meter connected therewith, a called subscriber's line, means normally dependent upon the operation of the meter for releasing the connection between the lines and means adapted 125 to be temporarily associated with the calling line for holding it energized and for breaking down the remainder of the connection without the meter being operated.

11. In a telephone system, the combina- 130

- tion of a calling subscriber's line, a cut-off relay and meter connected therewith, a called subscriber's line, means for connecting the two lines, means normally dependent upon 5 the operation of the meter for releasing the connection and means adapted to connect suitable potential between the cut-off relay and the meter so that the cut-off relay is held energized while the meter is caused to de-
10 energize.
12. In a telephone system, the combination of a calling subscriber's line, a meter connected therewith, a called subscriber's line, means for connecting the two lines, 15 means normally dependent upon the operation of the meter for releasing the connection and means adapted to be associated with the called line for holding it energized, for breaking down the connection and for pre-
20 venting the operation of the meter.
13. In a telephone system, the combination of a calling subscriber's line comprising a third conductor, a meter connected therewith, a cut-off relay, a called subscriber's line, 25 means for connecting the two lines, means normally dependent upon the operation of the meter for releasing the connection, a biased relay adapted to open the meter circuit, means adapted to be temporarily asso-
30 ciated with the called subscriber's line for holding it energized and means for connecting suitable potential between the cut-off relay and the meter for holding the cut-off relay energized and for actuating the biased
35 relay.
14. In a telephone system, the combination of a calling subscriber's line, a meter connected therewith, a device for feeding current to the trunk, a called subscriber's 40 line, a biased relay associated with the cur-
- rent feeding device and adapted to prevent the meter being operated, means for varying the current in the circuit comprising the two lines and the trunk and means adapted to be temporarily associated with the called line 45 for actuating the current varying means.
15. In an automatic telephone system, the combination of a calling subscriber's line, a meter connected therewith, a called subscriber's line, means for connecting the two lines, 50 means normally dependent upon the operation of the meter for releasing the connection and means for releasing the connection without the operation of the meter.
16. In a telephone system, the combination of an exchange, a calling subscriber's line connected thereto, a meter connected to such line, a second exchange, a called subscriber's line connected thereto, a trunk connecting the two exchanges, means adapted 55 to be temporarily associated with the calling line for holding such line energized, for breaking down the remainder of the connection and for preventing the meter being operated. 60
17. In a telephone system, the combination of an exchange, a calling subscriber's line connected thereto, a meter connected to such line, a second exchange, a called subscriber's line connected thereto, a trunk connecting the two exchanges, means adapted 65 to be temporarily associated with the called line for holding such line energized, for breaking down the connection and for preventing the meter being operated. 70
- In testimony that I claim the foregoing as my invention I have signed my name this eighth day of May, 1917. 75

HENRY JAMES HERINK.
